ABSTRACT: A linear cutter for the outer sheath of multiconductor cable has a supporting member with a groove for receiving the cable, a blade adjustably mounted on the support for limited protrusion into the groove, and a roller mounted to engage the cable and hold it in the groove in contact with the blade.

LINEAR CABLE SHEATH CUTTER

BACKGROUND OF THE INVENTION

Multiconductor cables require severing of the outer jacket in order to permit access to the wires therein for connection to other conductors. Various tools have been provided for slitting the sheath or jacket but these have generally had to be held in the hand while holding the cable with the other, thereby rendering difficult the accurate cutting of the sheath. Additionally, such cutting tools have not restricted the depth of cut, thereby permitting the possibility of cutting the insulation around an inner conductor. Additionally, previous cutting devices have generally required a special blade which must be sharpened from time to time or replaced.

SUMMARY OF THE INVENTION

The present invention is directed to a linear sheath cutter which can be mounted on a stationary support in order that the operator may use both hands for operating the cutter and holding the cable. The device is easy to use and permits an accurate depth of cut of the desired length.

Briefly stated, the invention includes a stationary support on which a cutter-holder is mounted, the holder having a longitudinal groove into which an adjustable movable blade protrudes a desired amount, and a roller mounted for engagement with the cable to hold it in the groove in engagement with the blade, whereby the cable may be pulled through the groove and its sheath cut.

BRIEF DESCRIPTION OF THE DRAWINGS

FIG. 1 is a side elevation of the device in accordance with the present invention;

FIG. 2, a front elevation thereof;

FIG. 3, a section on the line 3-3 of FIG. 2;

FIG. 4, a section on the line 4-4 of FIG. 1; and

FIG. 5, a fragmentary perspective of a cable with a longitudinal cut in its outer casing.

DESCRIPTION OF THE PREFERRED EMBODIMENT

With further reference to the drawings, the device includes a base or support member 10 which is mounted by fastening elements 11 to a work table or the like 12. The base has lon-

gitudinally extending groove 13 along the central portion of its upper surface, the groove being of a diameter to receive a multiconductor electric cable C of the type whose outer jacket is to be cut. Adjacent to one end of the base and centrally beneath the groove 13 is a slot 14 which receives a knife blade 15 pivotally mounted by a pin 16. The blade is preferably of conventional type such as that produced under the trade name "Exacto". A set screw 18 extends through the front of the base and engages a dull side of the knife 15 in order to position 10 its cutting edge 20 the desired distance into the groove 13.

An arm 22 is mounted by a pivot 24 upon a portion of the base which is spaced from the blade, the arm having a handle 25 on an upright portion 26 and carrying a roller 27 on an axle 28 which is mounted on the arm 22 and is substantially transversely disposed to the groove 13. The roller is preferably tapered, of reduced diameter at its central portion, for fuller engagement with a cable.

In the operation of the device, after the operator has set the blade to enter the groove the proper amount, the operator 20 grasps the cable C and lays the portion to be severed in the groove 13. With his other hand the operator depresses the handle 25 to apply pressure by the roller 27 onto the cable lying in the groove 13. With the parts thus positioned the operator then draws the cable outwardly, thereby causing the 25 knife to produce a linear cut in its jacket, the length of such cut being determinable by the operator.

I claim:

1. A linear cable sheath cutter comprising stationary support means, said support means having longitudinal groove means, cutter means, means mounting the cutter means on the support means with a portion extending into the groove means, and movable means mounted on the support means for engaging a cable lying in the groove means and applying pressure thereon to hold the cable against the projecting portion of 30 the cutter means, said pressure applying means comprising an arm pivotally mounted on the support means, and a roller mounted on the arm and extending generally transversely of said groove means.

2. The invention of claim 1, said arm mounted on one side 40 of said support means, said roller extending laterally from said arm across said support means.

3. The invention of claim 1, said roller being of reduced diameter at its portion which overlies the groove means.
